WATCH WRISTBAND

Theodore Hirsch, Detroit, Mich.

Application December 14, 1951, Serial No. 261,722

4 Claims. (Cl. 224—4)

1

My invention relates to a new and useful improvement in a watch wrist band intended for holding a wrist watch in position on the wrist of the wearer.

It is an object of the present invention to provide a wrist band of this type which will be simple in structure, economical of manufacture, durable, pleasing in appearance and highly efficient in use.

Another object of the invention is a provision of a wrist band of this type so arranged and constructed that it may be very easily released for removal from the wrist while at the same time, after being placed upon the wrist, it may be released for movement to observable position.

Another object of the invention is the provision of a wrist band of this type in which the band will be held snug against the wrist of the wearer, while at the same time being sufficiently yieldable to avoid any discomfort without in any manner rendering it likely that the wrist band would fall off the wrist.

Other objects will appear hereinafter.

It is recognized that various modifications and changes in the detail of structure illustrated may be necessary and it is intended that the present disclosure shall be considered but the preferred embodiment of the invention.

Forming a part of this application are drawings in which:

Fig. 1 is a perspective view of the invention showing it attached to a watch,

Fig. 2 is an elevational view of a pair of arms used in the invention,

Fig. 3 is an enlarged fragmentary elevational view of one side of the invention with parts broken away and parts shown in section,

Fig. 4 is a fragmentary view taken on line 4—4 of Fig. 3,

Fig. 5 is a sectional view taken on line 5—5 of Fig. 3,

Fig. 6 is a sectional view taken on line 6—6 of Fig. 2.

As shown in the drawings, the invention embodies a pair of rigid curved arms 8. These arms are duplicates of each other and consequently are designated by the same indicating numeral and each arm is provided, at one of its ends, with an opening 10 through which may be projected a pin 11 extending through a flange or lug 12 on the wrist watch 13, so that the arms 8 will thus be swingably connected at one of their ends to the opposite ends of the wrist watch 13. Carried on the other end of the arms 8 is a collar 14 having at its inner end an inwardly turned

2

flange or lug 15. This collar 14 is formed cup-shaped and has at its outer end an opening 24, into which slidably projects a flexible band 17. Carried by this band 17 is a collar 13, which is fixedly mounted thereon adjacent its inner end and which is provided with an outwardly projecting tongue 19. A sleeve or knuckle 16 is formed on the inner end of the flexible member 17 and through this sleeve or knuckle 16 is projected a pin 16a. A slot 16b is formed in the central part of the sleeve or knuckle and the end 20 of a coil spring 21 is positioned in this slot 16b and hooked over the pin 16a. The opposite end 22 of this coil spring 21 is hooked over the pin 11. The 10 opposite end of the flexible member 17 is similarly inserted into one of the arms 8 and the construction and connection of each arm is the same.

Covering each of the arms 8 is a covering 23 preferably formed from leather, or other suitable material, insofar as appearance and comfort on the wrist are concerned. This covering may also be of plastic, if desired, but it is preferred that it be of some soft material slightly moisture absorbent.

It is customary when wearing a wrist watch to have the watch positioned on the back of the wrist. When the present invention is in use a portion of the member 17 will be exposed, as these arms 8 do not meet. When the user desires to remove the wrist watch it is but necessary to pull on the member 17, which will cause the inner end to move outwardly of the arm 8 in which positioned. This outward movement will be, of course, against the tension of the spring 21 and 20 when the outward movement has proceeded so that the tongue 19 is positioned behind the lug 15 a slight lifting of the flange will cause the tongue 19 to engage behind the flange 15 and thus the wrist band is locked in open position, so that it may be easily and quickly removed from the wrist. When again placed upon the wrist the member 17 is moved in the opposite direction so as to disengage the tongue 19 from behind the lug 15, whereupon the springs 21 will 30 function to draw the wrist band into close contact with the wrist. In this outward movement of the inner end of the member 17 the pin 16a will engage against the front wall 25 at opposite sides of the opening 24, so that pulling the member 17 completely outwardly from the hollow arm 8 is prevented.

In this way I provided a wrist band which is very comfortable when worn and which lends itself to ornamental decoration so that a pleasing appearance may be obtained. The removal

and replacement of the wrist band is a simple and easy operation. Moreover, due to the construction of the wrist band, an economical structure has been arrived at.

What I claim is:

1. A wrist band of the class described adapted for use with a wrist watch, comprising: a pair of curved hollow arms, each of said arms being pivotally connectable at one of its ends to the opposite sides of a wrist watch; a flexible member insertable at its opposite ends into the free ends of each of said arms; a spring in each of said arms connected at one end in fixed relation to the arm in which positioned and at its opposite ends to the inner end of said flexible member; an engagement member carried on the free end of at least one of said arms; an engagement member carried by said flexible member within the engagement carrying arm and engageable therewith for normally preventing the pulling of said end into said arm by said spring.

2. A wrist band of the class described adapted for use with a wrist watch, comprising: a pair of curved hollow arms, each of said arms being pivotally connectable at one of its ends to the opposite sides of a wrist watch; a flexible member insertable at its opposite ends into the free ends of each of said arms; a spring in each of said arms connected at one end in fixed relation to the arm in which positioned and at its opposite ends to the inner end of said flexible member; an engagement member carried on the free end of at least one of said arms; an engagement member carried by said flexible member within the engagement carrying arm and engageable therewith for normally preventing the pulling of said end into said arm by said spring; and a member carried by the inner end of said flexible member engageable with a member on said arm for preventing withdrawal of said flexible member from said arm.

3. A wrist band of the class described comprising: a pair of hollow arms, each adapted for swingable connection at one of its ends with a wrist watch with which used; a spring member

positioned in each of said arms adjacent each of its swingable ends and in fixed relation thereto at one end; a flexible member inserted at its opposite ends into the free ends of said arms and connected to said spring, said spring normally tending to draw the ends of said flexible member inwardly of said arms; and inter-engaging means on the inserted end of said flexible member and the free end of the arm into which inserted for, upon engagement, resisting inward movement of the inserted end of said flexible member into said arm in response to the tension of said spring.

4. A wrist band of the class described comprising: a pair of hollow arms, each adapted for swingable connection at one of its ends with a wrist watch with which used; a spring member positioned in each of said arms adjacent each of its swingable ends and in fixed relation thereto at one end; a flexible member inserted at its opposite ends into the free ends of said arms and connected to said spring, said spring normally tending to draw the ends of said flexible member inwardly of said arms; and inter-engaging means on the inserted end of said flexible member and the free end of the arm into which inserted for, upon engagement, resisting inward movement of the inserted end of said flexible member into said arm in response to the tension of said spring; an abutment member on the free end of said arm and an engagement member carried by the inserted end of said flexible member for engaging said abutment member and preventing the pulling of said inserted end out of the arm into which inserted.

THEODORE HIRSCH.
